UNITED STATES PATENT OFFICE.

LEON F. HOFFMAN, OF FRANKLIN, PENNSYLVANIA, ASSIGNOR TO CHICAGO PNEUMATIC TOOL COMPANY, OF NEW YORK, N. Y., A CORPORATION OF NEW JERSEY.

CONTROL APPARATUS FOR COMPRESSORS.

Application filed February 8, 1927. Serial No. 166,624.

This invention relates to fluid compressors or pumps, more particularly air and gas compressors, the output of which is arranged to be varied automatically in response to the demands upon the receiver into which the compressed fluid is discharged. For efficient and economical operation it is customary to arrange such machines to unload in a plurality of stages, as three stage (full load, half load, no load) or five stages (full load, three quarter load, half load, quarter load, no load).

One object of the present invention is to improve the control and regulation of multi-stage compressors. Another object is to provide simplified and positively acting apparatus for this purpose. Another object is to permit convenient adjustment of the range of operation of such apparatus. Other objects will be apparent from the detailed description which follows:

In order to illustrate the invention and the manner of operation one concrete embodiment thereof is shown in the accompanying drawings in which:

Fig. 1 is a fragmentary and somewhat diagrammatical view of a variable volume compressor equipped with regulating apparatus in accordance with the present invention;

Fig. 2 is an enlarged side elevational view partly in section and partly broken away of the fluid pressure governor or regulating apparatus;

Figs. 3 and 4 are respectively side elevational and end elevational views of details of the regulating apparatus.

In Fig. 1 a variable volume compressor is indicated at A arranged to be controlled by a fluid pressure governor or regulating apparatus at B. Compressor A has unloading devices c, d, e and f arranged to be operated in the order given. Unloading devices c and d control clearance pockets a' and a'' so that the compressor is adapted to be unloaded in five steps. When none of the unloading devices is actuated the compressor operates at full load. On actuation of unloading device c, first stage unloading occurs and the left end of the compressor is half unloaded so that the compressor operates at $\frac{3}{4}$ load. On operation of the unloading device d, the opposite or right end of the compressor is half unloaded and the entire compressor operates at half load. On operation of unloading device e, the left end is entirely unloaded and

the compressor operates at quarter load. When device f is actuated the entire compressor is unloaded and operates at no load. The loading of the compressor in stages is in the reverse order.

The fluid pressure governor is shown in complete detail in Figs. 2, 3 and 4. The governor comprises a casing 5 providing a chamber 6 in which is disposed a diaphragm 7, providing a small chamber 8, having a connection 9 to the air receiver. Pressure fluid admitted to chamber 8 acts through diaphragm 7 upon a lever arm 10 pivoted at 11 and provided at its outer end with weights 12. Movement of lever 10 is transmitted through a yoke 13 to an arm or link from which is suspended a fluid control or pilot valve 15 of the Mason regulator type controlling passages 16 and 17 leading to opposite ends of a chamber in which reciprocates a piston 18. The fluid controlled by valve 15 may be water under pressure admitted at 19 and arranged to drain away at 20. Piston 18 is connected by head 21 and rod 22 to a balanced piston 23 movable in a cylinder 23^a. The space between the heads of piston 23 is always in communication with receiver pressure through an inlet pipe 24. Movement of piston 23 to the right serves to connect to receiver pressure in succession pipes 25, 26, 27 and 28 which lead to the unloading devices and effect respectively, first stage, second stage, third stage and fourth stage, or totally unloading stage. An additional pipe 29 beyond the limit of movement of piston 23 communicates with atmosphere and serves as a vent.

In order to ensure that the movement of pistons 18 and 23 shall be controlled in well defined steps to produce the progressive stages of unloading and loading of the compressor, compensating means are provided quickly to restore pilot valve 15 to neutral position after movement. To this end movement of piston 18 is transmitted by a head 30 to a rack bar 31, the teeth of which mesh with a pinion 32 secured to an eccentric rotatable cam 33 having spaced depressions 33^a in its periphery. A roller 34 carried by the lower arm of a bell crank 35 is maintained in contact with the periphery of cam 33 through the action of a spring 36. The upper arm of bell crank 35 is connected by a link 37 to the depending arm of a bell crank 38, the upper arm of which has pivotal connection with link 14.

The operation of the fluid pressure control apparatus as so far described is as follows. When the pressure against diaphragm 7 becomes sufficient to overcome weights 12, lever 10 moves upwardly carrying with it the yoke 13 and the link 14, thus lifting pilot valve 15 which uncovers the upper, and lower passages 16 and 17, thus admitting water against the left end of piston 18 and at the same time 5 venting the water from the opposite side of the piston. In consequence piston 18, as well as, piston 23 and rack bar 31 connected thereto move to the right and the unloading piston 23 connects pipe 25 to receiver pressure effecting 10 the first stage of the unloading of the compressor. Meanwhile cam 33 has been rotated until roller 34 has reached the first depression 33^a in the periphery of the cam. The cam has rocked valve crank 35 to the 15 left and this movement has been communicated by link 37 to bell crank 38 which has depressed link 14 and restored pilot valve 15 to its original neutral position so that the unloading mechanism has come to rest after 20 sufficient movement to effect first stage unloading of the compressor. Upon further increase in pressure in the receiver the next 25 position of the unloader piston 23 is assumed with pipe 26 uncovered and effecting second stage unloading of the compressor. Upon further increases in pressure the remaining 30 pipes 27 and 28 are uncovered in succession in an obvious manner. Upon a drop in pressure the unloading steps are retraced in order 35 to effect progressive loading of the compressor.

Means are provided for producing a dampening effect upon weight lever 10 the more positively to fix the extent of each movement 40 of piston 18 and for adjustably varying the range of operation of the regulating apparatus, such means being directly associated 45 with the compensating mechanism of the regulating apparatus. A fixed arm 39 extending from casing 5 and has a depending portion 39^a upon which is pivotally mounted a bell crank 40 or its equivalent. The horizontal arm of bell crank 40 supports a hollow casing 41 receiving therewithin in telescoping engagement a plunger rod 42 which is maintained in yielding contact with lever 10 by a spring 43, the tension of which is adjusted by a movable abutment member 44 held in adjusted position by lock nuts 45. 50 A link 41 serves adjustably to connect the aforesaid elements and the previously described compensating means, the depending arm of bell crank 40 having a series of holes 40^a therein, one of which is engaged by link 46 55 which has pivotal connection with a fixed portion of the casing for the control apparatus, as the base of the standard which supports bell crank 38.

The above described dampening and range 60 adjusting mechanism provides a yielding

buffer for lever 10 causing it to come to rest after a limited movement due to the force exerted by spring 43 when compressed. The compression of spring 43 compensates for the rise in air pressure and causes lever 10 to assume a definite position for each increase in air pressure so that for each definite air pressure there is a predetermined definite position 70 for piston 18 and consequently for the unloader piston 23. The difference in air pressure necessary to cause movement of pistons 18 and 23 from one definite position to the next in unloading the compressor may be varied by securing the left end of link 41 in a different hole 40^a in the depending arm of 75 bell crank 40. Assuming the difference in air pressure at which the successive movements of the piston occur is approximately three pounds, changing the rod to a hole 40^a nearer the pivot of bell crank 40 increases the 80 range between the successive steps and changing it to a hole 40^a more remote from the pivot decreases the range or pressure differential. Such changes in the connection between link 46 and member 40 vary the angle 85 of incidence of plunger 42 relative to lever 10. 90

From the above it will be apparent that the present invention provides automatic, positively operating mechanism for governing the unloading of a compressor in well defined steps or stages, that the improved form of compensating mechanism permits a more compact construction than has heretofore been possible, and that the dampening and range 95 adjusting means in cooperating with the compensating mechanism insures accurate functioning of the regulating apparatus and permits flexible and convenient control of the operating range or pressure differential between the steps or stages of unloading and 100 loading.

While a single cylinder compressor only has been shown in Fig. 1 merely for illustrative purposes, it is obvious that the principle of operation of the invention adapts the same 110 for the automatic control, in any desired number of loading and unloading steps, of varied types and arrangements of compressing equipment whether single or multiple cylinder, or whether single acting, double acting, 115 duplex, compound, or compound duplex. The regulating apparatus has been shown in what is now considered to be a preferred form but is obviously capable of modification and variation without departing from the 120 spirit of the invention. It is accordingly to be understood that the invention is not limited to the specific details of arrangement and form herein shown and described, but covers all changes, modifications and 125 adaptations within the scope of the appended claims.

I claim as my invention:

1. In a pump or compressor, the combination with a cylinder and a plurality of un- 130

- loading devices arranged to unload the cylinder in whole or in part, of automatic regulating apparatus for controlling said unloading devices comprising a pilot valve controlled by receiver pressure, means for returning the pilot valve to neutral position after each movement, and means including a rotatable member for actuating said first-named means.
2. In a pump or compressor, the combination with a cylinder and a plurality of unloading devices arranged to unload the cylinder in whole or in part, of automatic regulating apparatus for controlling said unloading devices comprising a pilot valve controlled by receiver pressure, means for returning the pilot valve to neutral position after each movement, and means including an eccentric cam for actuating said first-named means.
- 20 3. In a pump or compressor, the combination with a cylinder and a plurality of unloading devices arranged to unload the cylinder in well defined steps, of automatic regulating apparatus for controlling said unloading devices comprising a pilot valve controlled by receiver pressure, a reciprocable piston controlled by said valve, means for returning the pilot valve to neutral position after each movement, and means for actuating said first-named means comprising a rack member arranged to be moved as a result of the movement of said piston, and a stop member actuated by said rack member.
- 25 4. In a pump or compressor, the combination with a cylinder and a plurality of unloading devices arranged to unload and load the cylinder in well defined steps of automatic regulating apparatus for controlling said unloading devices comprising a pilot valve controlled by receiver pressure, a reciprocable piston controlled by said valve, means for returning the pilot valve to neutral position after each movement, and means for actuating said first-named means comprising a rack member arranged to be moved as a result of the movement of said piston, and an eccentric cam arranged for rotation by said rack member.
- 30 5. In a pump or compressor, the combination with a cylinder and a plurality of unloading devices arranged to unload and load the cylinder in well defined steps, of automatic regulating apparatus for controlling said unloading devices comprising a pilot valve controlled by receiver pressure, means for returning the pilot valve to neutral position after each movement, means including a rotatable member for actuating said first-named means, and means for adjusting the operating range of said apparatus.
- 35 6. In a variable capacity compressor, the combination with a cylinder and a plurality of unloading devices arranged to unload and load the cylinder in well defined steps, of automatic regulating apparatus for controlling said unloading devices including a pilot valve controlled by receiver pressure, compensating means for returning said pilot valve to neutral position after each movement and means associated with said compensating means for controlling the operating range of said apparatus.
- 40 7. In a variable capacity compressor, the combination with a cylinder and a plurality of unloading devices, arranged to unload the cylinder in well defined steps of automatic regulating apparatus for controlling said unloading devices comprising a weighted arm movable in response to receiver pressure, a pilot valve movable in response to movement of said arm, compensating means for returning said pilot valve to neutral position after each movement, and means associated with said compensating means and having contact with said arm for adjustably controlling the operating range of said apparatus.
- 45 8. In a variable capacity compressor, the combination with a cylinder and a plurality of unloading devices arranged to unload and load the cylinder in well defined steps, of automatic regulating apparatus for controlling said unloading devices comprising a weighted arm movable in response to receiver pressure, a pilot valve movable in response to movement of said arm, compensating means for returning said pilot valve to neutral position after each movement, means arranged to offer resistance to the movement of said arm in one direction, and a connection to a portion of said compressor for the purpose of controlling the operating range of said apparatus.
- 50 9. In a variable capacity compressor, the combination with a cylinder and a plurality of unloading devices arranged to unload the cylinder in well defined steps, of automatic regulating apparatus for controlling said unloading devices comprising a weighted arm movable in response to receiver pressure, a pilot valve movable in response to movement of said arm, compensating means for returning said pilot valve to neutral position after each movement, and means arranged yieldingly to resist movement of said arm in one direction, said last named means having an adjustable connection to a fixed portion of said compressor adjustably to control the operating range of said apparatus.
- 55 10. In a variable capacity compressor, the combination with a cylinder and a plurality of unloading devices arranged to unload and load the cylinder in well defined steps, of automatic regulating apparatus for controlling said unloading devices comprising a weighted arm movable in response to receiver pressure, a pilot valve movable in response to movement of said arm, compensating means for returning said pilot valve to neutral position after each movement, means including a plunger engaging said arm yieldingly to re-

sist movement of the latter, and means including a connection to said plunger means for changing the angle of said plunger relative to said arm thereby adjustably to control the operating range of said apparatus.

11. In a variable capacity compressor, the combination with a cylinder having a plurality of unloading devices, of automatic regulating apparatus for controlling said unloading devices comprising a weighted arm movable in response to receiver pressure, a pilot valve movable in response to movement of said arm, compensating means for returning said pilot valve to neutral position after each movement, means including a spring pressed plunger mounted above said arm to resist upward movement of the latter, and means establishing a connection between said plunger and said compressor whereby the angular position of said plunger relative to said arm determines the operating range of said apparatus.

12. In a variable capacity compressor, the combination with a cylinder having a plurality of unloading devices, of automatic regulating apparatus for controlling said unloading devices comprising a weighted arm movable in response to receiver pressure, a pilot valve movable in response to movement of said arm, compensating means for returning said pilot valve to neutral position after each movement, and means comprising a support, a plunger adjustably mounted on said support and arranged to resist movement of said arm, and means connecting said plunger to a fixed portion of said compressor for controlling the operating range of said apparatus.

13. In a variable capacity compressor, the combination with a cylinder having a plurality of unloading devices of automatic regulating apparatus for controlling said unloading devices comprising a weighted arm movable in response to receiver pressure, a pilot valve movable in response to movement of said arm, compensating means for returning said pilot valve to neutral position after each movement, and means comprising a support, a plunger engaging said arm yieldingly to resist movement of the same, a pivotal mounting for said plunger on said support, and a link connection for said mounting for controlling the operating range of said apparatus.

14. In a variable capacity compressor, the combination with a cylinder having a plurality of unloading devices, of automatic regulating apparatus for controlling said unloading devices comprising a weighted arm movable in response to receiver pressure, a pilot valve movable in response to movement of said arm, compensating means for returning said pilot valve to neutral position after each movement, and means comprising a support, a plunger engaging said arm yieldingly to resist movement of the same, a pivotal

mounting for said plunger on said support, and a link establishing an adjustable connection for said mounting for varying the operating range of said apparatus.

15. A fluid pressure governor for a variable volume compressor comprising a fluid control valve, means for effecting movement of said valve in response to variations in pressure, a movable member controlled by said valve, means for returning said valve to neutral position after each movement to cause said member to advance or recede in well defined steps, and means for varying the operating range of the governor and the pressure differential between the steps of said member.

16. A fluid pressure governor for a variable volume compressor comprising a fluid control valve, means for effecting movement of said valve in response to variations in pressure, a movable member controlled by said valve, compensating means actuated by movement of said member for returning said valve to neutral position after each movement, mechanism cooperating with said compensating means positively to determine the extent of each movement of said member, and means for varying the operating range of the governor and the pressure differential between movements of said member.

17. A fluid pressure governor for a variable volume compressor comprising a fluid control valve, means for effecting movement of said valve in response to variations in pressure, a movable member controlled by said valve, compensating means actuated by movement of said member for returning said valve to neutral position after each movement, mechanism cooperating with said compensating means positively to determine the extent of each movement of said member, and means for adjusting said mechanism to vary the pressure differential between any successive movements of said member.

18. The combination with a fluid control valve and movable member controlled thereby, of means for returning the valve to neutral position after movement, said means including a rotatable member arranged to fix the movement of said movable member at each action of the valve.

19. The combination with a fluid control valve and a movable member controlled thereby, of means for returning the valve to neutral position after movement, said means including an eccentric rotatable member arranged to fix the movement of said movable member at each action of said valve.

20. The combination with a fluid control valve and a movable member controlled thereby, of means for returning the valve to neutral position after movement, said means including an eccentric cam having depressions in its periphery arranged to fix the movement of said movable member at each action of said valve, and means for rotating said cam con-

comitantly with the movement of said movable member.

21. The combination with a fluid control valve and a movable member controlled thereby, of means for returning the valve to neutral position after movement, said means including an eccentric cam having depressions in its

periphery arranged to fix the movement of said movable member at each action of said valve, and rack and pinion means operated by said movable member for rotating said cam. 10

Signed by me at Franklin, Pennsylvania, this 4th day of Feb., 1927.

LEON F. HOFFMAN.
